(57) CLAIM

The ornamental design for a single-sole shoe with stripe and outpatch sole, as shown and described.

DESCRIPTION

FIG. 1 is a perspective view of an embodiment of our new design of a single-sole shoe with stripe and outpatch sole; FIG. 2 is a first side view thereof;

FIG. 3 is a second side view thereof;

FIG. 4 is a top view thereof;

FIG. 5 is a bottom view thereof;

FIG. 6 is a front view thereof; and,

FIG. 7 is a back view thereof.

The broken lines illustrating the half-moon patch and the heel stripe are for illustrative purposes only and form no part of the claimed design.

1 Claim, 6 Drawing Sheets
